Atty

UNITED STATES PATENT OFFICE.

HENRY C. GLASGOW, OF CHICAGO, ILLINOIS.

IMPROVEMENT IN CAR-COUPINGS.

Specification forming part of Letters Patent No. 41,767, dated March 1, 1864; antedated February 17, 1864.

To all whom it may concern:

Be it known that I, HENRY C. GLASGOW, of Chicago, in the county of Cook and State of Illinois, have invented certain new and useful Improvements in Car-Couplings; and I do hereby declare that the following is a full, clear, and exact description thereof, reference being had to the accompanying drawings and the letters and figures marked thereon, which form part of this specification.

In the said drawings, which are hereunto annexed, Figure 1 represents a plan or top view of my invention. Fig. 2 represents a side view thereof in section at the line *x* in Fig. 1. Fig. 3 represents an end view of the same; and Fig. 4 shows a plan view of the abutting end of the coupling, the top being removed.

Similar letters of reference in the several figures aforesaid denote corresponding parts of my invention.

The nature of my invention consists in so constructing a device for coupling together the cars composing a train that there shall be but little slack in the connections; that cars of unequal height may be coupled together in such a manner that the draft shall be horizontal; that the cars may be run together preparatory to being coupled without the necessity of any person's standing between or near the cars, and when the cars have been run together and are at rest the person whose duty it may be can go in between the cars and connect them without moving the train, and that the coupling may be accomplished automatically by simply running the cars together.

To enable those skilled in the art to understand how to construct and use my invention, I will proceed to describe the same with particularity, reference being made to the said drawings annexed.

A A' B b in the said drawings represent the abutting end of the coupling, and is provided with two or more recesses, as shown clearly in Fig. 3, whose depth from front to rear is such as to allow the coupling-link C to slide back within said recesses about one half the length of said link, leaving the other half thereof projecting out, as shown in Figs. 1 and 2. The parts of the aforesaid abutment marked A A' should be of cast-iron; the parts marked B of wood; the parts seen in Fig. 3, denoting the

end of the grain, which also project out a short distance beyond the other parts, so that when the cars come together the striking parts of the coupling shall be of wood, and the parts marked *b* of wrought or cast iron, though I prefer them of wrought-iron. These parts are firmly bolted together by the bolts marked *h* in the drawings. Through the center of the said abutment there is made a longitudinal slot extending through said abutment from top to bottom, which is marked *a*, in which the coupling-pin C moves. The said pin C passes through a movable slide marked *g*, which slides back and forth in a groove on the top of the abutment, as shown in the drawings. At the extreme end of the said pin, below said sliding plate *g*, there are projections which prevent the pin from being moved out of said plate, and the said plate is prevented from slipping out of the groove in which it moves by a suitable stop in the groove at the front end; or the grooves themselves need not extend fully to the end of the coupling. The purpose of this device is to prevent the pin from being lost and to sustain it in the position shown in Fig. 2 preparatory to coupling the cars together automatically, as hereinafter described.

e represents a wire attached to the pin C, and *f* a wire support for said wire *e*, the uses of which will be hereinafter explained.

I I represent two strong rods, which pass through the projections *a' a'* upon the said abutment, where they are confined by a screw or nut, thence passing through the plank E, so as to readily slide or move therein, and then passing or bending around the plank F, down behind said plank, and going back at the bottom of the coupling through said plank E, and being fastened to the abutment, as before described.

H H represent two strong rods, which are bent as shown, passing around the transom-beam of the car, (marked *J* in the drawings,) then extending forward and passing loosely through the front or end of the car, (marked *G*.) and the plank F is fastened at each end to the plank E, as shown. There is coiled around the said rods *H H*, between the planks E and F, a strong spiral spring, (marked *s* in the drawings.)

Fig. 4 shows a plan view of one of the blocks

B, showing small cast-iron blocks in the rear of the recess, against which the end of the link rests when pressed back, containing also the recess b', in which the pin can lie without being bound by the pressure of the link, so as to be withdrawn readily when desired.

When the partitions b are made of wrought-iron, the blocks B' in the upper and lower recess may be cast upon the parts A and A', and the block B' in the middle recess or recesses can be bolted or otherwise attached to the block B; but if the partitions b are of cast-iron then the interior blocks, B', may be cast upon the parts b.

The operation of my invention is as follows: When the cars are run together, the abutting ends of the blocks B strike together, the link C at the same time entering into that recess in the coupling of the adjacent car, which is of the proper height, the edges of the partitions b being beveled down so as to insure the entering of the link, as aforesaid. If the pin c be in the recess b' at the time of running the cars together, it is then raised up, moved forward to the proper position, and then dropped through the link C, thus coupling the cars firmly together. On the said pin c there is a projection which prevents the pin from dropping down through the coupling, as said projection always rests upon the link C, the weight of the pin retaining the coupling-link in a horizontal position; but if the pin c be arranged as shown in Fig. 2 when the cars are run together, then by the contact of the cars the said pin is caused to fall or drop through the said link, thus coupling the cars automatically, for, as the cars are run together the shock compresses the springs s s, and thus the pin c approaches nearer to the end of the car G, and the upper end of the bent rod or wire e presses against G and forces the upper end of the pin forward, thus throwing the said pin into an upright position, when the lower end slips from its support and drops through the link, as aforesaid. The said springs s s also serve to relieve the sudden shock occasioned by the contact of the cars with each other when being run together, and also when the train is started, for when the cars are run together the pressure forces the plank E, sliding upon the rods H and I, toward the bunter

D; but the springs s s, by their elasticity, gradually retard the motion of the said plank E, so that it comes against the said bunter very gently, occasioning no violent shock whatever, and when the cars are started the draft brings the plank F and bunter D toward the plank E, the springs s s operating in the same manner and with the same result.

By the arrangement of the said springs s s and the sliding rods H I the cars may be coupled without any considerable slack between them, as the springs at one side of the coupling may be compressed, while those on the other side are not, so as to provide for any curves in the road, while at the same time the faces of the abutments may rest closely against each other.

The said springs and sliding rods are also capable of a vertical as well as lateral adjustment, so as to provide for the up-and-down or jumping motion of the cars without the necessity of having a slack motion between the cars.

In the bunter D there is a removable block, d, which may be of such thickness as to suit the more or less elastic force of the springs s s. When the springs s s have greatest elastic force, the thickness of said removable block should be greatest, and when they are weakened by use the block d may be made smaller, so as to allow the springs to check the violence of the shock before the plank E comes in contact with said block.

Having now described my improvement in car-couplings, I will specify what I claim as new therein and desire to secure by Letters Patent—

1. The construction, combination, and arrangement of the castings A A', blocks B B', and partitions b with the sliding planks E F, rods H I, and springs s s, as and for the purposes herein shown and described.

2. In combination with the foregoing, the pin c, with the stop or rest c', and bent rod e, and the slide g, moving in a longitudinal slot, a, and the recess for the pin b', arranged as and for the purposes specified.

HENRY C. GLASGOW.
